WINCH

Donald Robert Stonely, Wandsworth, London, England, assignor to Gyral Gears Limited, Wandsworth, London, England, a British company

Application April 6, 1940, Serial No. 328,303
In Great Britain December 4, 1939

6 Claims. (Cl. 254—187)

This invention relates to winches and like winding apparatus and has for its object to provide a construction or arrangement embodying improved means for driving a cable winding drum and means for automatically disengaging the drive in case of an overload.

According to the invention a winch or like winding apparatus is provided comprising a drum upon which a rope or other flexible element is adapted to be wound wherein rotation of the drum is effected by operating gear including a clutch adapted to disengage when a driving effort in excess of a predetermined value is applied and a gyrating gear engaging an internally toothed ring fixed within said winding drum.

According to another feature of the invention the winding drum is mounted within a casing and means are provided to transmit the rotary movement of the operating device to an element held stationary during normal operation, should a stoppage occur due to binding of slack cable between the drum and casing.

Reference will now be made to the accompanying drawings which illustrate by way of example a construction according to the invention and in which:

Fig. 1 is a side elevation of a winch,

Fig. 2 is a vertical section of the winch taken on the line 2—2 of Fig. 1,

Fig. 3 is a vertical section of the winch taken on the line 3—3 of Fig. 2,

Fig. 4 is a sectional plan taken on the line 4—4 of Fig. 2,

Fig. 5 is a side elevation showing one application of the winch shown in Figs. 1 to 4,

Fig. 6 is a detail view, on an enlarged scale, of the driving clutch, and

Fig. 7 is a section taken on the line 7—7 in Fig. 6.

Referring first to Figs. 1—4, the device shown comprises a casing 1 in which is mounted a winding drum 2 which is supported on trunnions journaled in the side plates of the casing. The periphery of the drum 2 is provided with a helical groove 3 adapted to receive successive convolutions of a winding cable 55 to be wound thereon.

Within the drum 2 there is mounted an internal gear 4 secured thereto by means of bolts 5, which serve also to secure one cheek 6 of the drum in position. The gear 4 is engaged by a planet gear 7 of slightly smaller diameter than the gear 4, which is rotatably mounted on bearings on an eccentric 8, formed or mounted on the end of a hollow shaft 9 which is itself located within a hollow shaft 10 to which it is keyed by 55

means of a feather 11. The shaft 10 is journaled within one trunnion of the drum 2 and carries at its outer end a ratchet wheel 12 and also one element 13 of a dog clutch having teeth 14. The dog clutch also comprises a complementary element 15 which is rotatably mounted on the protruding stub end of the hollow shaft 9, and carries a squared sleeve to receive and fit into a correspondingly shaped hub 16 of a crank 17 having a handle 18 by which the winch is turned.

The two elements of the clutch device are drawn together by means of a spring 19 which is mounted on a bolt member 20, the spring and bolt member being located within the hollow shaft 9. The spring is a compression spring and bears at its outer end upon an inwardly directed flange 21 formed on the outer end of the hollow shaft 9. At its other end the spring 19 bears upon the head 22 of the bolt member 20. The bolt member 20 is attached at its outer end to the member 15 by means of a nut 23. A cap 24 screwed into the member 15 may be provided to cover the nut 23.

At its inner end the shaft 9 is journaled in the inner end of a hollow shaft 25 rotatable in bearings 38 carried in a trunnion of the winding drum, which trunnion is itself rotatable in bearings 37 in the wall of casing 1. The inner end of the shaft 25 terminates in a flange or disc 39 having two diametrically opposed slots 40 formed therein engaged by radial projections 41 formed on a floating ring 26 whose opposite side is formed with a further pair of radial projections 27 disposed at right angles to the first pair and engaging radial slots 42 formed in the gear 7. This arrangement embodying the floating ring 26 is a development of the well known Oldham coupling and allows the gear 7 to make gyratory movements relatively to the shaft 25 to which it is coupled.

The ratchet wheel 12 formed on the end of the shaft 10 is engaged by a pawl 31 pivoted on the side plate of the supporting stand 1 and urged into engagement with the ratchet wheel by a spring 32 to permit rotation of the shaft 9 in the cable winding direction and prevent retrograde rotation thereof, the pawl 31 being disengageable from the ratchet wheel 12 to permit rotation of the shaft 9 in a cable unwinding direction.

A braking arrangement is provided for controlling rotation of the drum 2, said arrangement comprising one or more brake shoes 33 mounted on one side plate of the supporting

stand 1, and urged by means such as a spring 34 into engagement with a suitable friction surface 35 formed on or attached to the drum 2. A layer of friction material 36 may be attached to each brake shoe. This braking arrangement which is continually effective whether the winch is being operated to wind or unwind, is provided to obtain a "damping" effect and thereby prevent the winding drum from gathering too much momentum when the cable is pulled out freely. It will be appreciated that by disengagement of the pawl 31 from its ratchet wheel 12 turning of the drum 2 in the opposite sense may be brought about. The casing is provided with a standard or foot 44 for assisting in the support of the casing as hereinafter described.

The driven clutch member 13 carries a ring 45 around which is wrapped a friction brake band 46 one end of which is anchored to the casing at 47 and the other end of which is connected to an adjusting screw 48 whose action is to increase or decrease the compression of a spring 49 and thereby enable a tension of the said brake band to be applied sufficient to steady the operation of the device but not interfere with its operation at a normal speed. In order to relieve the driving means of the effect of the brake during the cable winding operation, the brake band 46 is preferably arranged to act on a ring 13^a rotatably mounted on the periphery of the ring 45 and provided with ratchet teeth 13^b with which spring pressed pawls 13^c on the ring 45 cooperate, these ratchet teeth and pawls being arranged to engage and drive the ring 13^a and thereby apply a braking action and thus control the unwinding of the cable, but to act idly and thus render the brake ineffective during the winding of the cable.

The shaft 25 has mounted thereon a ratchet toothed wheel 51 engaged by a pawl 52 pivotally mounted on a pin 53 carried in the wall of the casing and having a hand retracting arm 54.

To provide for the stowage of the handle 17-18 when not in use, a socket 56 is formed in the standard 44 through which the handle grip 18 is passed while the crank portion 17 extends parallel to the side of the casing so that the hub 16 passes over a stud 57 fixed in the side of the casing. The handle is temporarily locked in operating position by means of a plunger 58 mounted in a socket 59 fixed to the hub 16, said plunger being adapted to engage in a recess formed in the sleeve on the clutch member 15 and from which the plunger can be withdrawn against the action of a spring 60 by pulling outwardly an operating knob 61. This arrangement also serves to hold the handle against accidental detachment from the sleeve of the clutch member 15 during operation of the handle, the plunger 58 engaging in a surrounding groove 62 in the said sleeve.

The mechanism above described operates as follows:

The clutch members 13 and 15 are normally held by the spring 19, in the position of engagement shown in Fig. 2 so that when the crank 17 is rotated, the rotary movement is transmitted through shafts 10 and 9 to the eccentric 8. Rotation of the eccentric 8 causes the gear 7 to move in a gyroscopic sense around the gear 4. In the construction illustrated, the handle 18 is turned in a clockwise direction (looking at Fig. 1) to wind cable onto the drum 2, and owing to the fact that the gear 7 cannot rotate, the drum 2 rotates also in a clockwise direction. The gear 7 tends to rotate in an anti-clockwise direc-

tion but is prevented from turning by engagement of the radial projections 41 with the fixed disc 39 which permit only relative radial movement of the ring 26. The gyroscopic motion of the gear 7 produces a reaction upon the toothed ring 4, which is thereby turned in a similar direction to that of the shaft 9, carrying with it the drum 2 to wind or unwind the cable 55 onto or from the periphery, depending upon the direction of rotation. During these operations the pawl 53 engages ratchet wheel 51 and holds shaft 25 against anti-clockwise rotation, so long as the cable is under load.

Should the load on the drum 2 increase unduly, the reaction set up between the two parts 13 and 15 of the clutch device develops an axial component determined by the form given to the teeth 14, as shown in Figs. 6 and 7, which causes parts 13 and 15 to separate against the action of the spring 19 whereby slipping of the clutch takes place. In this manner, overloading of the device is prevented and the attention of the operator is drawn to the overload.

As long as a weight is being hauled, lifted or lowered, the cable 55 is held taut but when the cable is slack it is liable to jump the grooves 3 and become wedged between the drum 2 and the inner wall of the casing 1.

This result is particularly liable to occur if an attempt is made to unwind with a slack cable. Should the handle 18 be rotated anticlockwise with a slack cable, springs 34, acting through brake shoes 33, prevent the drum from rotating and the mechanism idles or "free wheels," because the handle 18 is being rotated in an anti-clockwise direction, to unwind the cable, but with the drum stopped, clockwise rotation is transmitted to shaft 25 by reason of gear 7 rolling around within the now stationary gear 14, pawl 52 permitting ratchet wheel 51 to slip past it in a clockwise direction. This operation produces a free-wheel effect of the driving mechanism inside the stationary drum 2, which prevents further unwinding of the cable and gives an audible signal to the operator by reason of pawl 52 slipping from tooth to tooth. The operator then lifts pawl 52 by rocking the arm 54 and pulls out the cable by hand. This is particularly advantageous because, should the cable become wedged between the drum and the casing the free wheeling action releases the drum and prevents it from becoming more tightly wedged.

This operation can also be performed should a stoppage occur during winding in, in which case the cable which has jumped grooves 3 can be pulled out by hand and subsequently re-wound.

The arrangement just described is advantageous because the wedging of the drum can be a gradual operation, offering insufficient resistance to cause the clutch members 13 and 15 to slip until the parts have become extremely tightly wedged.

When lowering a load the pawl 31 is lifted and the handle turned in an anti-clockwise direction (looking at Fig. 1) until the load rests upon the ground or other support. After this, any further turning of the handle will not pay out additional cable because this produces a slack cable condition, brake shoes 33 stop the drum and the free-wheel action just described comes into play immediately, the drum stopping and shaft 25 starting to rotate in a clockwise direction, with pawl 52 idly slipping past the teeth of ratchet wheel 51. The drive can be applied to shaft 25 by transferring the winding handle 17-18 thereto,

to apply a direct drive through the planet gear 7 to rotate the drum 2 for obtaining a quick wind-in, when no load is on the cable. Further, by retracting the pawl 52 from the ratchet wheel 51, a free pull-out can be obtained when the cable is loaded or pulled.

When winding-in is completed the attention of the operator is drawn thereto by slipping of the clutch 13—14 through which the shaft 9 is driven.

The application of the invention to a winch for use in loading bombs into aircraft is shown in Fig. 5. In this arrangement, the winding handle is dispensed with and operation effected by a motor 66 although the construction remains such that a winding handle can be interchangeable with the motor. The casing is supported by the standard 44 which has laterally extending feet 67 while the hood 64 is supported by a location member 68 fixed in the aircraft structure. The casing is also provided with a supporting pad 69 on which it is supported in addition to the feet 67 when tilted to a rest position.

The cable 55 passes out of the casing through an extension 63 the outer end of which terminates in a hood 64 enclosing a pulley 65 around which the cable passes and terminates in a vertical portion 55^a to which a load is adapted to be attached in any convenient manner.

I claim:

1. A winch comprising a casing, a drum mounted rotatably in the casing and adapted to wind a cable on its periphery, an internal gear fixed to said drum, a gyratory gear within and cooperative with said internal gear, an operating shaft mounted rotatably in one side of the casing and having an eccentric thereon cooperative with said gyratory gear for gyrating it within the internal gear to rotate said drum in one or the other direction to wind or unwind the cable, a clutch connected to said operating shaft for driving it, said clutch being releasable by a driving effort in excess of a predetermined value, ratchet means cooperative with said operating shaft and operable to permit rotation thereof in a direction to effect rotation of the drum in a cable winding direction and releasable to permit rotation of said shaft in a cable unwinding direction, a second shaft mounted rotatably in the other side of the casing in alignment with said operating shaft and capable of rotation independently thereof, a floating coupling interposed between said second shaft and gyratory gear operative to sustain rotative reaction of said gyratory gear while compensating for the gyratory movement thereof, and ratchet means cooperative with said second shaft and operative to lock the latter against rotation in one direction under the reaction of the gyratory gear while rotating the drum in a cable winding direction but permitting rotation of said second shaft in the opposite direction under an excess reaction of the gyratory gear while rotating the drum in cable unwinding direction.

2. A winch comprising a casing having a cable outlet, a drum rotatable in the casing and adapted to have a cable wound thereon and passed

- through said outlet, an internal gear carried by said drum, a gyratory gear within and meshing with said internal gear, drive means for gyrating said gyratory gear within said internal gear, 5 means for preventing rotation of said gyratory gear about its axis when it is gyrated in a direction to wind up cable on said drum by said drive means and being automatically operable to allow said gyratory gear to both gyrate and 10 rotate freely about its axis in the opposite direction when driven by said drive means in said opposite direction when there is no load upon the cable, or when the cable becomes wedged between the drum and casing, so as to effect a free-wheeling action and arrest rotation of said drum.
3. The winch defined in claim 2, wherein said drive means includes a clutch automatically disengageable to release said gyratory gear when the latter opposes rotation with a torque in excess of 20 a predetermined magnitude, for relieving the device of abnormally high stresses.
4. In a winch construction, a stationary casing having aligned openings in opposite walls, a rotor structure having an internal gear and spaced hollow hubs, bearing means journaling said hubs in said casing openings, a drive shaft journalled within one hub portion and a reaction shaft journalled within the other, said shafts having their neighboring ends telescoped and journalled one 25 within the other inside said rotor, an eccentric on said drive shaft, a spur gear rotatable on said eccentric and meshing with said internal gear, and means for coupling said spur gear to said reaction shaft.
5. The winch construction defined in claim 4, 30 together with means for preventing rotation of said shafts in one direction, and selectively operable means for driving either of said shafts in the opposite direction, for effecting either a slow or fast wind-in of cable.
6. In a winch construction, a drum mounted 35 for rotation, an internal gear carried by said drum, a drive shaft mounted for independent rotation about the axis of said drum and having an eccentric portion, a spur gear rotatably mounted on said eccentric portion and constantly meshing with said internal gear, a reaction shaft mounted for coaxial rotation with said drive 40 shaft and drum, a flexible coupling connecting said spur gear to said reaction shaft, means for rotating said drive shaft to cause said spur gear to gyrate within said internal gear, and locking means for restraining said reaction shaft against rotation, so as to cause gyration of said spur gear to effect rotation of said drum to wind 45 cable upon, or unwind cable from said drum, depending upon the direction of rotation of said drive shaft, said locking means being operable to positively lock said reaction shaft against rotation when said spur gear is gyrated in a direction to wind the cable on the drum, and automatically operable to allow counter-rotation of said reaction shaft without effecting rotation of said drum when there is no load on the cable and said spur gear is gyrated in a cable unwinding 50 direction.
